SHIELDED COLOR GRID STRUCTURE FOR CATHODE-RAY TUBES

Craig S. Nunan, Berkeley, and Renn Zaphiropoulos, Oakland, Calif., assignors to Chromatic Television Laboratories, Inc., New York, N. Y., a corporation of California

Application June 21, 1954, Serial No. 438,238

15 Claims. (Cl. 315—14)

The present invention relates to cathode-ray tubes of a type adapted to effect the reconstitution of polychrome images. More particularly, the invention relates to a color structure for such cathode-ray tubes which is readily adaptable to shielding and hence can be made to possess relatively low radiation characteristics.

Cathode-ray tubes having a grid of essentially parallel wires located adjacent to a striped phosphor screen are now known in the art. Such a structure may in some cases serve as one component of an electron lens system to focus the beam electrons into a pattern of thin lines nominally registered with the discrete phosphor areas of the screen, as is exemplified by Ernest O. Lawrence in his United States Patent No. 2,692,532 granted October 26, 1954.

One type of cathode-ray tube incorporating the above principle (which may be termed "post-deflection-focusing") is designed with a relatively large number of narrow component-color phosphor strips laid down in a predetermined sequence to form a screen, or target electrode. These phosphor strips luminesce, when impacted by the cathode-ray beam, in various component colors of the image to be synthesized. Purely as an example, the order in which the phosphor strips are laid down may be red, green, blue, green, and so on, bearing in mind that the color of a phosphor as used herein relates to the color of the light emitted therefrom which reaches the eye of an observer. An electrically-conductive coating overlies the phosphor strips, and is produced in some preferred manner such as by aluminization.

In order that the path of an electron arriving at the phosphor screen from the cathode emitter may be controlled in a selective manner in the vicinity of the target, a grid assembly is located adjacent to the phosphor screen and, with the latter, comprises a color structure of a type to which the present invention is related. Such a grid is formed of a large number of wires, or linear conductors, extending in the same general direction as the phosphor strips, and lying in the path of electrons directed to the target electrode from the electron gun of the cathode-ray tube. The wires of the grid assembly are electron-optically related to the phosphor strips so that, in this electron-optical sense, there is a wire aligned with each blue strip, and similarly a wire aligned with each red strip. It should be borne in mind that this electron-optical alignment incorporates whatever spacing corrections are necessary to compensate for variations introduced into the tube operation by changes in the instantaneous angle of impingement of the cathode-ray beam as it scans the target, and also by changes in deflection sensitivity at portions of the target electrode asymmetrically located with respect to the tube axis. However, these corrections form no part of the present invention, and are mentioned merely as an aid in understanding the operation of a tube of the nature set forth. All of the wires associated with the red strips are connected to a common terminal, while the "blue" wires are similarly joined together electrically.

Between the actual, or nominal, plane of the wire grid assembly and the conductive coating on the phosphor strips a difference of potential is established. By properly choosing the magnitude and polarity of this potential difference, a series of converging electrostatic fields for the beam electrons is created. These converging fields (which may be likened in an optical sense to cylindrical lenses) cause the beam electrons arriving at the wire grid from the electron gun of the tube to form a fine line structure on the phosphor target. It will be appreciated that the particular scanning operation by means of which the beam electrons are caused to trace a raster at the plane of the grid wires has no direct geometrical relationship to the actual line structure developed on the target electrode, the latter being determined solely by the configuration of the wires of the grid assembly.

Inasmuch as the grid wires, as stated above, are electron-optically aligned with the phosphor strips, a zero potential difference between the "red" and "blue" terminals of the grid will result in the beam electrons undergoing a focusing action alone, and hence these electrons may be caused to impinge the target within the boundaries of a particular strip such as green. If the conductors associated with the red strips are made relatively positive with respect to the conductors electron-optically related to the blue strips, then the beam electrons will be subjected to an auxiliary, or micro-, deflection over and above that due to the deflection providing the raster, so that the lines of impingement of such electrons will now lie within the respective boundaries of the red strips. Similarly, electrons will strike the blue strips when the wires associated with such strips are suitably positive with respect to the "red" wires. Different component colors of the image are thus displayed according to the potential difference (if any) existing between the two sections of the grid wire assembly.

In designing one grid structure of the above type, the wires are maintained in position relative to the phosphor strips by means of spacer elements. The spacing between the plane of the grid wires and the phosphor-coated surface of target is critical in many respects, and must remain substantially unchanged during operation of the cathode-ray tube. One preferred construction in which the grid wires and the phosphor screen are formed as a unit is illustrated and described by the applicant Renn Zaphiropoulos in his United States Patent No. 2,683,833 granted July 13, 1954.

In the Zaphiropoulos assembly, a light-transmissive base plate (which may be of glass) is employed as a target backing. This base plate is secured to a grid frame by the strand conductors, or wires, of the grid. A pair of spacer bars is affixed to one surface of the base plate and defines a window, or target, area therebetween which may be coated with phosphor strips having the desired color characteristics. Means are provided for securing the electrically-conducting wires to the frame so that these wires extend across the window, or target, area of the base plate and are positioned therefrom by the spacer bars.

Inasmuch as the grid structure being described is designed for color switching, or micro-deflection of the beam in the vicinity of the target electrode, the wires or linear conductors are divided in two sets of alternate strands, and suitable means are provided for applying potentials to each set of strands. To carry this out, the frame is divided into two sections, with each section serving a set of strands. Consequently, in this form of construction, the glass plate is "sandwiched" between the wires of the grid, on one hand, and the two frame sections, on the other. These two frame portions are pressed together by the tension of the wires associated

with the outer frame portion, and this pressure acts to hold the frame, base plate, and wires in a unitary assembly. A suitable insulating means between the two sections of the frame are also provided in order to permit different potentials to be applied to the two sets of grid wires.

Under certain circumstances, desirable results may be obtained with a color structure of the nature set forth by dividing the unitary assembly of grid wires and phosphor plate into two separate sub-assemblies, one of which is composed of the grid wires and their associated frame (or frames) and the other sub-assembly being composed of the phosphor-coated plate and its mounting means. One type of construction in which two such sub-assemblies are employed is set forth in a copending United States patent application of Leslie J. Cook and Lawrence D. Quaglia, Serial No. 404,038, filed January 14, 1954. The structure of the Cook et al. application, however, is intended to be utilized in conjunction with a multiple-gun cathode-ray tube. To adopt this so-called "separate-plate-from-grid" design to a single-gun polychrome cathode-ray tube, the construction of the grid supporting members must be modified so that each set of wires may be insulated one from the other.

In the Cook et al. disclosure the grid wire and frame assembly is fabricated as a unit, and the phosphor plate, spacer bars, and mounting elements are fabricated as a second unit. These two sub-assemblies are then brought together at the proper time so that the wires of the grid assembly fall within notches in the spacer bars associated with the plate assembly. Thus a structure results which is similar (as far as operating characteristics are concerned) to the unitary design set forth in above-mentioned Zaphiropoulos United States Patent No. 2,683,833.

The so-called "separate-plate-from-grid" design, set forth by Cook et al. may be formed by a grid fabricating method in which the strand conductors are wound around the rectangular grid frame in an uninterrupted fashion. This results in two sets, or groups, of parallel wires which lie in different planes. These wires are then forced into substantially coplanar relation by means (which include the spacer bars) when the plate assembly is brought into juxtaposition with the wire grid unit. There is nothing shown by either Cook et al. which would permit the so-called "separate-plate-from-grid" design to be used in connection with a color grid construction in which each set of grid wires is attached to its associated frame section by hooking the wire over a projection on the frame, laying down the wire across the raster area of the base plate, hooking it over a projection on the opposite side of the same frame, bringing it back across the raster area of the base plate, and so on. This particular back-and-forth method of construction may be called for descriptive purposes the "wrap around" design.

A basic feature of color grid structures of this "wrap around" type is that the frame sections are fabricated of conducting material, and that the hooks which serve to support the grid wires are cut into two oppositely-disposed edges of each frame section. Thus each strand of the wire grid directly contacts the frame because of its being "wrapped around" the hooks. Consequently, a single electrical contact to the frame section serves as a contact to each one of the strand conductors through the material of the frame section itself. In other words, each of these frame sections actually serves as a lead to each strand conductor of one set of grid wires. When color switching is carried out at R. F., the R. F. switching current passing through the frame section causes the latter to act as an efficient radiator of R. F. energy. In actual practice, it has been found that the amount of energy radiated by such a grid structure during tube operation exceeds the limits which have been set as commercially-acceptable values. Consequently, interference with other electronic devices in the neighborhood of a tube incorporating such a grid structure is a problem, and has been

found to constitute a disadvantage toward the wide acceptance of such a color-reproducing tube. It is a principal feature of the present invention to reduce this radiation from the color grid assembly to a point where interference with other electronic devices is at a minimum.

According to a feature of the present invention, a substantially rectangular grid frame is employed around which a continuous conductor is wound in an uninterrupted fashion so as to form a first set of strand conductors having double the spacing desired for the wires of the finished grid assembly. A second continuous conductor is then wound around a separate support so as to form a further set of strand conductors lying between the conductors formed by the first winding operation, with each set of conductors being insulated from the other at points where they would normally contact the metal of the frame. Inasmuch as the above design does not comprehend a physical connection between the wire strands and the glass base plate upon which the colored phosphor strips are deposited, these two members are brought into juxtaposition so that the individual wire strands are indexed in notches in a pair of spacer bars carried by the glass plate. When the plate (and its support) are secured to the grid frame, complete color structure results. All of the operations mentioned above may be carried out by simple mechanical means thus permitting a relatively low cost of manufacture.

One object of the present invention, therefore, is to provide an improved type of cathode-ray tube designed for the reconstitution of polychrome images.

A further object of the present invention is to provide a grid structure, for cathode-ray tubes designed especially but not exclusively for polychrome image reproduction, in which the various portions of the grid may be separately fabricated and then these portions assembled into a unitary structure.

A still further object of the present invention is to provide a grid structure, for cathode-ray tubes designed especially but not exclusively for polychrome image reproduction, in which the strand conductors of the grid are wound in such fashion that they are electrically insulated from the main frame section itself, and only contact especially designed hook strips which are so positioned with respect to the frame section that the former may be readily shielded to thereby minimize undesired radiation therefrom.

Other objects and advantages of the present invention will be apparent from the following description and from the drawings, in which:

Figure 1 is a semi-diagrammatic view of a cathode-ray tube, showing in cross-section a color structure in accordance with the present invention;

Figure 2 is a plan view of the color structure of Figure 1 as seen from the electron gun end of the cathode-ray tube;

Figure 3 is a detailed view of a portion of Figure 1;

Figure 4 is a perspective view of a portion of Figure 3, showing the design of the grid frame itself;

Figure 5 is a perspective view of a portion of Figure 3, showing in further detail the manner in which the two sets of grid wires are supported by the end pieces of the frame;

Figure 6 is a perspective view of a part of the entire color assembly after the grid wire sub-assembly and the base plate sub-assembly have been brought into proper operating relation;

Figure 7 is a plan view of a portion of the target area of Figure 2, showing one preferred relationship between the grid wires and phosphor strips;

Figure 8 is a plan view of a portion of Figure 2, showing in addition one manner in which connections may be made from the input connector to the four hook strips of the color structure; and

Figure 9 shows one preferred method in which the hook strips and the leads from these hook strips to the input

connector on the cathode-ray tube may be shielded so as to prevent excessive R. F. radiation.

Referring now to the drawing, there is shown in Figure 1 a cathode-ray tube certain parts of which are conventional. For example, in the neck end of the tube, and within the envelope 10, there is an indirectly-heated cathode 12 which acts as a source of electrons for development into a scanning beam. The latter is indicated schematically by the trace 14. Adjacent to, and partially surrounding, the cathode 12 is a control grid 1, or electrode, 16 suitably apertured to permit the passage of electrons which are subsequently formed into the beam 14. The control grid 16 functions in the usual manner to modulate the emitted stream of electrons in accordance with the potential applied thereto relative to the cathode 12. Also in the neck end of the tube there is provided a first anode or grid 2 (identified by the reference numeral 18) to which suitable potentials may be applied so as to result in an initial acceleration of the electrons emitted from the cathode 12. Adjacent to grid 2 there is provided a second anode, or grid 3 (reference numeral 20), for supplying an additional acceleration to the electrons.

Deflecting coils, comprising a horizontal pair 22 and a vertical path 24, are provided for the usual scanning purposes. Obviously the terms "horizontal" and "vertical" are used herein in a descriptive sense only. Thus the electron beam 14 is caused to scan a phosphor-coated target, or light-transmissive base plate 26, to produce light which is visible through the end wall 28 of the envelope 10.

Shown in Figure 2 is a substantially rectangular support, or frame, 30 adapted to fit within the envelope of the cathode-ray tube. This frame 30 is made up of a pair of oppositely-disposed L-shaped channel members 32, which form two sides of the frame, and a pair of flat end pieces 34, which form the remaining two sides. The L-shaped members 32 are respectively secured to the end pieces 34 by some suitable method such as welding. Purely as an example, the side members 32 and end pieces 34 of the frame 30 may be fabricated of type #430 stainless steel. As perhaps best shown in Figure 4 of the drawings, each of the flat end pieces 34 forms a relatively sharp angle with the plane of the side members 32. Two inserts 36 (one of which is clearly illustrated in Figure 4) are respectively welded or otherwise secured to the two side member 32 so as to strengthen the frame and also to form a window area, the outline of which is best seen by reference to Figure 8. This "window" has substantially straight top and bottom edges, and side boundaries which are curved in the manner illustrated. A plurality of mounting holes 38 are provided in the flanged portion of each side member 32 so as to permit the color structure to be secured to the inner surface of the cathode-ray tube.

Although not shown in the drawing, four tabs, or fingers, are welded or otherwise affixed to the inner surface of the cathode-ray tube envelope 10, and extend toward the end wall 28. When the frame 30 is positioned within the tube approximately in the location shown in Figure 1, these four tabs or fingers will be aligned with the mounting holes 38, and bolts or other securing means (not shown) may be passed through these holes 38 to best securely mount the frame 30 in position. It might be mentioned at this time that it is not necessary to provide electrical insulation between the frame 30 and the tabs which mount the frame 30 in position within the cathode-ray tube, inasmuch as it will be later brought out that the frame 30 may operate at the potential of the cone without in any way affecting the application of color-switching potentials to the two sets of grid wires. In any event, the particular means for mounting the frame 30 within the tube envelope forms no part of the present invention, and any suitable means which rigidly positions the frame 30 approximately in the location shown by Figure 1 may be utilized.

It has been brought out above that the present invention contemplates the employment of two sub-assemblies, each of which may be fabricated independently. It then contemplates that these two sub-assemblies will be brought together to form a complete color-control structure. This will be later set forth in connection with a description of Figure 6. For the present, however, the construction of the grid wire sub-assembly will be described—that is, the assembly consisting of the frame 30 and the two sets of interleaved conductors which extend across the open window area thereof.

It has been fully brought out in the above-mentioned Zaphiropoulos United States Patent No. 2,683,833, that a continuous filamentary conductor may be wound back-and-forth around a series of hooks wound on each of two oppositely-disposed edges of a single frame member. In other words, each continuous conductor is attached to its associated frame section by hooking the conductor over a projection on the frame, laying down the wire across the open area of the frame, hooking it over a projection on the opposite side of the same frame, bringing it back across the open frame area, and so on. In other words, this constitutes a back-and-forth operation which (with a single filamentary conductor) leaves the parallel wires produced across the window area to have a spacing substantially twice that required in the finished color structure. A second continuous conductor is then wound back-and-forth around the hooks on a second frame section electrically insulated from the first frame section. The wires produced by this second winding will lie between the wires produced by the first winding operation, so that a grid structure will result in which the wire spacing is substantially equal to that desired for color image reproduction.

A generally similar technique is employed in connection with the grid assembly of the present invention, except that modifications are made in the particular structure employed to hold the wires in position. As will perhaps best be shown by reference to Figures 3 and 5, the frame end pieces 34 are not notched or grooved in the manner of the frame pieces of the Zaphiropoulos application above referred to, but instead serve merely as a supporting means for those members which actually hold the wires. The actual wire-retaining members of the present invention are in the form of strips having a generally U-shaped configuration, and are provided on one edge with a series of hooks adapted to engage each turn of the single filamentary conductor employed to form one set of wires. As will perhaps be best shown by Figure 3, there are two hook strips for each end piece 34, a first inner strip and a second outer strip. Each inner hook strip has its open end slipped over the projecting edge of one of the end pieces 34 after a layer of insulating material 40 has been laid over both those surface portions of the end piece which the first inner hook strip is designed to encompass. Each inner hook strip 42 extends for the entire length of its respective end piece 34 from one of the L-shaped side members 32 to the other L-shaped member 32. In other words, each inner hook strip 42 takes the place of the hooks which were actually cut into the material of the frame section itself in the above-mentioned Zaphiropoulos assembly. It will be noted, especially from Figure 3, that when the wire is hooked over one of the projections on the inner hook strip 42, then the continuous filamentary conductor, which forms the first set of wires 44 (Figure 5) will exert a "pulling" action upon the hooks of the strips 42 which acts to pull the latter down more tightly upon the upper edge of their respective end pieces. Thus the tension of the first set of wires 44 acts to hold the inner hook strips 42 tightly compressed against the outer edge of their respective end pieces 34 through the insulating layers 40 which are present therebetween. The first winding operation with the first filamentary conductor is thus completed so that a set of wires 44 extends in substantially parallel coplanar relationship across the window area of the frame 30.

When this first winding operation has been accomplished, a further insulating layer is placed over the outer surface of each of the two hook strips 42. Each such insulating layer is designated in Figures 3 and 5 by the reference numeral 46. On top of each insulating layer 46 an outer hook strip 48 is placed, these outer hook strips 48 having the same generally U-shaped configuration as the inner hook strips 42, and being provided with a series of hooks on that edge associated with the hooked edge of each inner strip 42. The second continuous filamentary conductor is then wound back-and-forth around the hooks on these outer strips 48, so as to result in a second set of linear conductors 50 lying between the first set of conductors 44, with the two sets of hook strips being insulated from one another by the presence of the insulating layers 46. As best seen by reference to Figures 3 and 5, each outer hook strip 48 is isolated electrically from its associated inner hook strip 42 and also from the frame section 30 by means of the two insulating layers 40 and 46. Thus the electrical potential of the frame 30, as will be shown below, has no bearing upon the potentials that may be applied to the hook strips 42 and 48 and hence to the two sets of grid wires 44 and 50.

Due to the angular relationship between the frame end pieces 34 and the L-shaped side members 32, the tension of the grid wires 44 and 50 (as exerted through the hook strips 42 and 48) acts to maintain these strips tightly wedged against their respective end pieces 34, and precludes any possibility that the hook strips will slip off the end pieces 34 and thus render the cathode-ray tube inoperative. Furthermore, each of the hook strips 42 and 48 acts as an electrical lead to each one of the linear conductors 44 and 50 associated therewith, and, since the hook strips have a relatively low electrical resistance, identical potentials may be applied to all of the wires of each of the two sets.

Purely as an example, the frame 30 may have approximately 400 linear conductors extending across the open window area thereof, 200 of these being associated with the inner hook strips 42 and the remaining 200 being associated with the outer hook strips 48. These two sets of wires may be respectively formed from two continuous filamentary stainless steel conductors of approximately .006" diameter.

In order to prevent electrical contact between the conductors 44 and 50 as they pass over the respective edges of the end pieces 34 prior to extending across the window area of the frame 30, and also to insulate each set of conductors from the frame itself, the outer edge of each frame piece 34 is recessed in such a manner as to receive an elongated insulating element preferably having the form of one of the glass rods 51 and 52. Each such rod is provided with a series of precisely-formed grooves, with the distance between the grooves being equal to the distance desired between adjacent conductors 44 and 50 of the finished color structure (see Figure 6). It will be noted especially from Figures 3 and 5 that if the recess formed in each of the end pieces 34 is of proper configuration, the pressure or tension of the wires 44 and 50 will act to hold the grooved insulators in their respective recesses in the end pieces 34 without any such securing means as cement. The structure disclosed is thus extremely resistant to damage by shocks of a physical nature such as may occur during handling or transportation of the cathode-ray tube.

The hook strips 42 and 48 are preferably composed of some high-electrical-conductivity material such as aluminum, silver, or silver-plated steel. The insulating layers 40 and 46 may be of any suitable type which will withstand the bakeout temperatures reached during processing of the cathode-ray tube. One substance which has proven to be satisfactory in practice comprises resilient insulating tape of a vitreous nature.

Although in some instances the hook strips 42 and 48 may themselves serve as leads to each of the individual conductors 44 and 50 of the wire grid assembly, it has

become customary in practice to employ a separate electrical lead which extends throughout the length of each of the hook strips. Each such lead, which may be a strip of very thin aluminum, is placed between each of the hook strips and the insulating layers 40 and 46 so that an electrical potential may be applied to each of the hook strips 42 and 48 which is independent of the potential of the frame 30. These electrical leads may be of a design as shown in Figure 5, where the ends of two of the leads are shown as extending beyond the frame end pieces 34. Furthermore, by employing integral leads of this nature, it is unnecessary to make a connection between separate input leads and each of the hook strips 42 and 48.

Although a back-and-forth winding operation satisfactory in principle for producing the grid of the present invention has been fully set forth in the above-mentioned Zaphiropoulos United States Patent No. 2,683,833, nevertheless it might be helpful to state herein that, following the placing on their respective end pieces 34 of the inner insulating layers 40, the inner hook strips 42 and the lead strips A, the winding process begins by attaching the end of the first continuous filamentary conductor to a hook at the extreme end of one of the hook strips 42. The first set of grid wires 44 is then wound preferably by rotating the frame structure 30 so that the wire starting from the hook just mentioned goes around the first grooved glass insulator 51, extends across the window area of the frame 30, falls in the appropriate groove on the other grooved insulator 52, and is wound around the extreme end hook on the opposite one of the inner hook strips 42. At this point, the direction of rotation of the frame 30 is reversed, and the winding procedure continues in a similar manner until the first set of grid wires 44 is obtained. The second insulating layer 46 is then placed over the inner hook strip 42, the lead strips B placed over the insulation 46, the outer hook strips slipped over the lead strips B, and then the second set of grid wires 50 wound in the same manner as that described above so as to result in two interlaced sets of grid wires across the window area of the frame 30. It will be clear that all of the hook strips, leads, and grooved cane pieces 51 and 52 are held firmly in place by the tension of the wires 44 and 50. Furthermore, it will also be evident that each of the hook strips 42 and 48 is insulated electrically from the frame 30 as well as from the other hook strip, and that the leads A and B to each of the four hook strips will have extending portions (indicated best in Figures 5 and 9).

The light-transmissive backing or base plate 26 carries on one of its surfaces a series of phosphor strips laid down in a manner such as will be described in connection with Figure 7. That is, the sequence of these phosphor strips may be, for example, red, green, blue, green, red, green, and so on. For proper operation of the tube being described, it is desirable that each of the strand conductors of the grid be aligned, in an electro-optical sense, with the red and blue phosphor strips. To bring this about, a pair of insulating spacer elements, or bars, 54 are securely affixed to one surface of the base plate 26 in a manner best shown in Figures 2, 3 and 6. These spacer bars, as well as the base plate 26, may comprise boro-silicate glass, but in any event should have the same coefficient of expansion. These spacer bars 54 perform the dual function of aligning the coplanar wire strands with the phosphor strips, and also maintain the wire strands at a uniform distance from the surface of the base plate 26.

The base plate 26, with its pair of spacer bars 54, is mounted relative to the frame 30 so that it occupies the position best shown in Figures 3 and 6. Referring to the latter figure, a pair of plate anchoring bars 56 (one only being illustrated) extend across that surface of the phosphor-coated base plate 26 opposite to the side which is coated with the phosphor and which carries the spacer bars 54. In other words, the plate anchoring bars 56 extend across that surface of the base plate 26 nearest to

the end wall 28 of the cathode-ray tube, and opposite to that side impinged by the cathode-ray beam. The plate anchoring bars 56 lie near and parallel to two oppositely-disposed edges of the base plate 26, and in substantially parallel relationship to the spacer bars 54 except that they are on the opposite surface of the plate therefrom. These plate anchoring bars 56 serve the purpose of positioning the plate 26, and each bar 56 is associated with a pair of anchoring arms 58. These anchoring arms 58 are each of substantially Z-shaped configuration, and are designed to have one projecting portion secured to the plate anchoring bar 56 and the other projecting portion secured to one of the frame side members 32. When the anchoring arms 58 are secured in position by spot-welding or other means, the phosphor plate 26 is precluded from movement relative to the frame 30 by means of the pressure of the plate anchoring bars 56 on the surface thereof, which pressure is maintained by the anchoring arms 58.

When the phosphor-coated base plate 26 is brought into its desired position relative to the frame 30 (as best shown in Figure 6), the grid wires of the two sets 44 and 50 will fall within appropriate grooves cut into the upper edge of each spacer bar. These grooves are similar to those cut into the outer edge of each of the insulating members 51 and 52, so that the alignment of the wires, initially brought about by the insulating members 51 and 52, is enhanced and maintained by the grooves of the spacer bars. As a result of these two aligning means, the spacing of the wires as they extend across the open area of the frame 30 is maintained substantially constant during operation of the cathode ray tube.

The relative position of the individual conducting strands, or grid wires, and the red, green and blue phosphor strips which are applied to that surface of the base plate 26 impacted by the electron scanning beam is shown in Figure 7. Although the particular arrangement of the phosphor strips forms no part of the present invention, nonetheless a desirable arrangement has been shown to consist of a sequence of strips such as red, green, blue, green, red, green, and so on. The strip widths are chosen in accordance with tube design so as to provide electro-optical rather than physical relationships between the grid wires and the phosphor strips. Each adjacent pair of grid wires is accordingly designed to subtend (in an electro-optical sense) a portion of the target electrode surface which includes phosphor areas of each of the component colors. Generally speaking, however, it may be said that the distance between adjacent grid wires is substantially equal in one dimension to a single elemental area of the image to be resolved by the cathode-ray tube.

It has been stated above that one of the principal objects of the present invention is to reduce the amount of radiation produced by a color structure of the type being described to a point which is within limits which have been designated as being commercially acceptable. In this connection, it has been found to be unnecessary to shield the grid wires themselves, inasmuch as radiation from the latter is almost negligible. This is because each grid wire carries only an extremely small fraction of the charging current, and, since this current is in opposite directions in adjacent wires, field radiation is effectively cancelled from this portion of the assembly. The principal source of radiation is in the frame structure itself, since the latter ordinarily serves as a lead to carry the charging current to the grid wires. However, the disclosure of the present invention does not make the grid frame part of the circuit which carries this charging current, and hence the grid frame as a unit need not be shielded. The only effective shielding necessary is that around the leads from the input terminal of the cathode-ray tube up to and including the point where the charging current is fed to each one of the grid wires.

It has been stated above that the electrical circuit embracing these elements includes only the inner hook strips 42, the outer hook strips 48, and the two lead strips A and B which carry the charging current from the input

terminal of the cathode ray tube to the hook strips 42 and 48 and hence to the grid wires 44 and 50. Referring now to Figure 8, it will be seen that if shielding is provided from the input coaxial connector 60 of the cathode ray tube along the leads A and B, and over and encompassing the outer hook strips 48, then the amount of undesired radiation from the cathode-ray tube will be materially reduced.

One preferred method of accomplishing the above objective is to provide a pair of end shields (best shown in Figure 8 and identified by the reference numerals 62 and 64) and a single side shield 66. The details of one end shield 62 and of the side shield 66 are best shown in Figure 9. Reference to this latter figure shows that each end shield (both end shields are identical) is composed of an inverted U-shaped open-ended sheet-metal member which is slipped over one of the outer hook strips 48 in the manner shown in the drawing. This end shield surrounds all of the outer surface of its associated hook strip in the manner shown, and of course is spaced therefrom so as to have no electrical contact therewith. This end shield extends for the length of the hook strip and consequently for the length of the associated frame end piece 34. Each end shield is provided along one of its edges with a flanged projecting portion 68 (Figure 9) which lies flat against the surface of one of the members 36 (see again Figure 8) which faces the electron gun of the cathode-ray tube. After the end shield 62 (for example) is placed in the position best shown by Figure 9, the flanged portion 68 thereof is secured to the surface of the member 36 by some preferred method such as spot-welding. The purpose of this operation is to hold the end shield 62 spaced apart from the outer hook strip 48 so as to contain the latter substantially within its confines as best shown in Figure 9. Substantially all radiation from the hook strips 42 and 48 is thus prevented from extending beyond the end shields, inasmuch as the latter are directly connected both physically and electrically to the frame 30 which in itself carries no color-switching potentials.

However, since the leads A and B do carry the color-switching currents, it is desirable that these leads be shielded throughout their length, and this is accomplished in part by the side shield 66. This side shield 66, as best shown in Figure 9, is of hollow tubular construction (although it may be somewhat rectangular in cross-section), and extends from the point where the leads A and B from the coaxial connector 60 enter the vicinity of the frame side member 32 up approximately to those points where these leads come in contact with their respective hook strips 42 and 48. Actually this side shield 66, as shown in Figures 8 and 9, may be composed of a single tubular member extending substantially throughout the length of one frame side member 32. At its center point, one of its surfaces is cut open (as again best shown by Figure 9) so as to form a "middle outlet" through which the two sets of leads A and B may be passed.

The side shield 66 may be secured to the frame side member 32 in any suitable manner, such as by a pair of steel brackets 70 one of which is shown in Figure 9. Each steel bracket may again be spot-welded (as shown at 72, for example) to the frame side member 32. Obviously the leads A and B must be kept out of electrical contact with the side shield 66, inasmuch as the latter is at frame potential, but since the leads are composed of material (such as aluminum) having a fairly rigid nature, it is possible to maintain them in somewhat of a central position with respect to the shield surfaces.

Both the two end shields 62 and 64, as well as the single side shield 66, may be formed of aluminum sheet, while the brackets 70 are preferably composed of some material such as stainless steel.

If it is found that excessive radiation results from the leads A and B from the point where they emerge from the coaxial input connector 60 up to the point where they enter the side shield 66 (as best shown in Figure 8)

it is obviously possible to place another flexible aluminum shield (not shown) over the leads A and B throughout this distance.

It has been found in practice that in some cases currents may be induced in the frame 30 when R. F. switching potentials are fed to the grid wires 44 and 50 through the leads A and B. If these induced currents become excessive, it is possible to place a sheet of aluminum foil over the two surfaces of each of the end pieces 34 (Figure 4) before the first layer of insulation 40 is placed over the outer edges of these frame pieces. This results in an appreciable reduction in the induced currents in the frame, and may, in some cases, have a marked effect upon the switching power requirements.

In summary, therefore, a few of the outstanding features of the design described above are that it appreciably reduces the amount of R. F. radiation from the color structure and hence reduces the amount of interference with other electronic apparatus in the neighborhood of the cathode-ray tube; it permits a greater usable area for viewing the reproduced image, inasmuch as the frame and pieces are at an angle to the plane of the grid wires rather than substantially parallel thereto as has been the case in previous tube constructions; it involves fewer expensive silver-plated parts, and hence the tube of the present disclosure may be constructed at lower cost; the shielding structure employed herein is simple in design and can be added to the color assembly with very little additional effort; and, finally, use of the so-called "separate-plate-from-grid" design permits these two sub-assemblies to be fabricated at different locations with a consequent saving in production cost. Furthermore, any defect in either of the two sub-assemblies will not necessitate discarding the entire color unit.

Having thus described the invention, what is claimed is:

1. In a grid structure designed for incorporation into a cathode-ray tube adapted to reconstitute images in a plurality of colors, the combination of a grid-carrying frame composed of a pair of oppositely-disposed side members and a pair of oppositely-disposed end pieces, defining, with said side members, a frame window area, said pair of end pieces being of generally flat configuration and being respectively secured to said pair of side members so as to form an angle in the range between zero and 90° with the plane defined by said side members, a layer of insulating material covering the outer edges and at least a portion of each surface of each of said pair of frame end pieces, a pair of U-shaped strips respectively overlying the outer edges of said pair of frame end pieces and also said insulating layer, and a plurality of linear conductors supported by said strips so as to lie across the window area of said frame in substantially parallel alignment.

2. In a grid structure designed for incorporation into a cathode-ray tube adapted to reconstitute images in a plurality of colors, the combination of a grid-carrying frame composed of a pair of oppositely-disposed side members and a pair of oppositely-disposed end pieces, defining, with said side members, a frame window area, said pair of end pieces being of generally flat configuration and being respectively secured to said pair of side members so as to form an angle of between zero and 90° with the plane defined by said side members, a layer of insulating material surrounding the outer edge of each of the said pair of frame end pieces and at least a portion of each surface thereof, a pair of U-shaped retaining strips respectively overlying the outer edges of said pair of frame end pieces as well as said insulation, a second layer of insulation overlying the outer surface of each of the said pair of retaining strips, a second pair of U-shaped retaining strips overlying the last-mentioned insulating layers, a first set of linear conductors supported by said first-mentioned pair of U-shaped retaining strips so as to lie across the window area of said frame in sub-

stantially parallel fashion, and a second set of linear conductors supported by said second pair of U-shaped retaining strips so as also to lie across the window area of said frame in substantially parallel fashion with the linear conductors supported by said first strip lying intermediate the linear conductors supported by said second strip.

3. The combination of claim 2, further comprising means for applying potentials to each of the first and second pairs of strips and consequently to the sets of linear conductors respectively associated therewith, each of the said potentials applied to the said pairs of strips being different from each other and from the operating potential of said frame.

4. The combination of claim 3, in which the means for applying potentials to the said two pairs of strips which are different from the potential of said frame includes means for insulating each of the said sets of linear conductors from said frame, said last-mentioned means including a pair of insulating rods of vitreous material respectively receivable in a pair of recesses respectively formed along the edges of each of said pair of flat end pieces opposite to those edges overlaid by said retaining strips, the said linear conductors passing over a portion of the surface of each of the said pair of insulating rods in such a manner as to be kept from electrical contact with said frame.

5. In a grid structure designed for incorporation into a cathode-ray tube adapted to reconstitute images in a plurality of colors, the combination of a grid-carrying frame composed of a pair of oppositely-disposed side members and a pair of oppositely-disposed end pieces defining, with said side members, a frame window area, said pair of end pieces being of generally flat configuration and being respectively secured to said pair of side members, a pair of retaining strips respectively overlying the outer edges of said pair of frame end pieces, a sheet of insulating material between each of said pair of retaining strips and its associated frame end piece so as to electrically insulate each of said strips from its associated frame end piece, and a pair of radiation-suppressing members formed of sheet-like material at least partially surrounding each of said retaining strips and spaced apart therefrom, said pair of radiation-suppressing members being secured along one edge thereof to a surface of said frame in the vicinity of said retaining strips.

6. In a grid structure designed for incorporation into a cathode-ray tube adapted to reconstitute images in a plurality of colors, the combination of a grid-carrying frame composed of a pair of oppositely-disposed side members and a pair of oppositely-disposed end pieces defining with said side members a frame window area, said pair of end pieces being of generally flat configuration and being respectively secured to the said pair of side members so as to lie at an angle in the range between zero and 90° to the plane defined by said side members, a layer of insulating material respectively surrounding the outer edge of each of said pair of frame end pieces and at least a portion of the surface thereof, a U-shaped hook strip overlying each said insulating layer, a second insulating layer overlying the outer surface of each of said pair of U-shaped hook strips, a second pair of U-shaped hook strips respectively overlying the said last-mentioned insulating layers, a first continuous conductor wound back-and-forth between corresponding hooks on said first pair of U-shaped hook strips so as to lie across the window area of said frame in the form of a plurality of linear conductors substantially parallel to one another, a second continuous conductor wound back-and-forth between corresponding individual hooks on said last-mentioned pair of U-shaped hook strips so as to lie across the window area of said frame in a form of a plurality of linear conductors substantially parallel to one another and lying intermediate the individual conductors associated with said first U-shaped hook strips, means for insulating the linear conductors

formed by the said two winding operations from the metallic material comprising said frame, and a pair of radiation shields respectively surrounding the said second pair of U-shaped hook strips and spaced apart therefrom, each of the said pair of radiation shields being affixed to a surface of said frame which is electrically insulated from each of the two pairs of U-shaped hook strips by at least one of the said layers of insulating material.

7. The combination of claim 6, further comprising conducting leads to each of the said two pairs of hook strips, whereby potentials may be applied to each of the said two pairs of hook strips which are different from the potential applied to said frame.

8. The combination of claim 7, further comprising a tubular shield for the leads to each of the said two pairs of hook strips, said tubular shield substantially completely enclosing the two pairs of leads for at least a portion of their length and being respectively secured to one of the said pair of oppositely-disposed frame side members, said tubular shield having an opening substantially intermediate thereof to permit emergence of said leads.

9. In a grid structure designed for incorporation into a cathode-ray tube adapted to reconstitute images in a plurality of colors, the combination of a grid-carrying frame composed of a pair of oppositely-disposed side members and a pair of oppositely-disposed end pieces defining, with said side members, a frame window area, said pair of end pieces being of generally flat configuration and being respectively secured to said pair of side members so as to lie at an angle in the range between zero and 90° to the plane defined by said side members, an insulating layer overlying at least a portion of the surface of each of said pair of end pieces, a pair of U-shaped hook strips respectively overlying said insulating layers, a second insulating layer overlying each of the said first U-shaped hook strips, and a second pair of U-shaped hook strips respectively overlying said second insulating layers so as to be electrically insulated from said first pair of U-shaped hook strips and also from the said pair of frame end pieces, a first continuous conductor wound back-and-forth between corresponding individual hooks on said first pair of U-shaped hook strips so as to lie across the window area of said frame in the form of a plurality of linear conductors substantially parallel to one another, a second continuous conductor wound back-and-forth between corresponding hooks on said second pair of U-shaped hook strips so as to lie across the window area of said frame in the form of a plurality of linear conductors inter-leaved with the conductors associated with said first-mentioned U-shaped hook strips, electrical connections to each of the said hook strips, a phosphor-coated base plate, a pair of spacer bars respectively secured near opposite edges of said phosphor coated base plate, and means for bringing said plate into juxtaposition with said frame so that each of said spacer bars contacts the said interleaved conductors, thereby maintaining said conductors substantially equidistant from the phosphor coating on said base plate across the frame window area.

10. The combination of claim 9, in which each of said spacer bars is grooved at spaced points along its outer edge, with the said interleaved conductors respectively falling within the said grooves.

11. The combination of claim 10, in which a U-shaped

shielding member overlies each of the said pair of outer hook strips throughout its length and is spaced apart therefrom, each of the said pair of shielding members being respectively secured to a surface of said frame adjacent to one of the said pair of end pieces.

5 12. The combination of claim 11, in which leads are provided to each of the said two pairs of hook strips, further comprising a shielding member for said leads in the form of a hollow tube enclosing said leads for at least a portion of their length and respectively secured to one of the side members of said frame.

10 13. In a grid structure designed for incorporation into a cathode-ray tube adapted to reconstitute images in a plurality of colors, the combination of a grid-carrying

15 frame composed of a pair of oppositely-disposed side members and a pair of oppositely-disposed end pieces defining, with said side members, a frame window area, said pair of end pieces being of generally flat configuration and being respectively secured to said pair of side members so as to lie at an angle other than zero to the plane defined by said side members, a plurality of linear conductors arranged side-by-side in substantially parallel relationship, means for supporting said plurality of linear conductors by said pair of end pieces so that the former extend across the window area of said frame in essentially coplanar fashion, and further means for precluding electrical contact between said frame and each conductor of the said plurality.

20 14. In a grid structure designed for incorporation into a cathode-ray tube adapted to reconstitute images in a plurality of colors, the combination of a grid-carrying frame composed of a pair of oppositely-disposed side members and a pair of oppositely-disposed end pieces of generally flat configuration defining, with said side members, a frame window area, a plurality of linear conductors arranged side-by-side in substantially parallel relationship, means for supporting said plurality of linear conductors by said pair of end pieces so that the former extend across the window area of said frame in essentially

25 coplanar fashion, and further means for precluding electrical contact between said frame and each conductor of the said plurality.

30 15. In a grid structure designed for incorporation into a cathode-ray tube adapted to reconstitute images in a plurality of colors, the combination of a grid-carrying frame composed of a pair of oppositely-disposed side members and a pair of oppositely-disposed end pieces of generally flat configuration defining, with said side members, a frame window area, a plurality of linear conductors arranged side-by-side in substantially parallel relationship, means for supporting said plurality of linear conductors by said pair of end pieces so that the former extend across the window area of said frame in essentially

35 coplanar fashion, means for precluding electrical contact between said frame and each conductor of the said plurality, means for connecting each conductor of the said plurality to a source of energy, and means for shielding at least a portion of said last-mentioned means to

40 reduce undesired radiation of energy therefrom.

45 16. A grid structure according to claim 14, in which said means for connecting each conductor of the said plurality to a source of energy includes a strip of electrically-conducting material extending transversely of the said parallel conductors and lying adjacent to but spaced apart from the surface of one of said frame end pieces, and in which said shielding means includes a metallic member at least in part enclosing said strip, said metallic member being supported by said frame and operating sub-

50 stantially at the electrical potential of the frame.
